UNITED STATES PATENT OFFICE

166,572

FLOOR POLISHING MACHINE

Harold J. Pond, Minneapolis, Minn., assignor to
Advance Machine Company, Minneapolis, Minn.

Application September 20, 1951, Serial No. 16,689

Term of patent 14 years

(Cl. D9—2)

To all whom it may concern:

Be it known that I, Harold J. Pond, a citizen of the United States, residing in Minneapolis, county of Hennepin, and State of Minnesota, have invented a new, original, and ornamental Design for a Floor Polishing Machine, of which the following is a specification, reference being had to the accompanying drawings, forming part thereof.

Figure 1 is a perspective view of a floor polishing machine showing my new design.

Figure 2 is a fragmentary top plan view thereof with a major portion of the handle broken away.

Figure 3 is a rear view thereof with a portion of the handle bar broken away.

I claim:

The ornamental design for a floor polishing machine, as shown.

HAROLD J. POND.
